UNITED STATES PATENT OFFICE.

HAROLD A. NEWCOMB, OF WILKINSBURG, PENNSYLVANIA, ASSIGNOR TO WESTINGHOUSE ELECTRIC AND MANUFACTURING COMPANY, A CORPORATION OF PENNSYLVANIA.

LIGHTNING-ARRESTER.

1,289,521.

Specification of Letters Patent. Patented Dec. 31, 1918.

Application filed May 3, 1915. Serial No. 25,466.

To all whom it may concern:

Be it known that I, HAROLD A. NEWCOMB, a citizen of the United States, and a resident of Wilkinsburg, in the county of Allegheny and State of Pennsylvania, have invented a new and useful Improvement in Lightning Arresters, of which the following is a specification.

My invention relates to protective devices for electrical circuits, and it has particular reference to that class of apparatus commonly designated as lightning arresters, although it will be understood that the function of these devices is not confined to the safe dissipation of lightning disturbances only but also includes the safe dissipation of discharges arising from all over-voltage disturbances.

It is important that a device of the aforementioned character shall act as a sort of electrical safety valve to discharge to ground or to dissipate, in some way, all high-potential disturbances without allowing the line current to flow continuously over the path initially established by the high-potential discharges. In accordance therewith, my lightning arrester precludes the line current from maintaining the arc established by the high-potential discharges.

My invention comprises a lightning arrester consisting of an evacuated bulb or envelop in which the pressure is considerably below normal atmospheric pressure. The electrodes, one of which is associated with a line conductor in any well-known manner, such as being connected thereto directly or through a spark gap, or through a resistor, and the other of which is adapted for a ground connection, furnish a low-resistance discharge path for over-voltage disturbances, but impose a prohibitively high-resistance path to the continuous flow of line current of normal voltage.

For a better understanding of the nature and scope of my invention, reference may be had to the following description and the accompanying drawing in which Figure 1 is a cross-sectional view of a device embodying a form of my invention, and Fig. 2 is a modified form of the device shown in Fig. 1.

By referring to Fig. 1, it will be noted that a line conductor 1 which, in this instance, is shown as being directly connected to a protective device 2 embodying a form of my

invention, is connected to ground 3 through a discharge path 4 extending between two electrodes 5 and 6 of the device 2. The device 2 comprises an evacuated glass bulb or envelop 7. The electrode 5, which is of filamentary form, is sealed in the envelop 7 in any well known manner. In a device constructed by me, I used the well-known tungsten seal which I have found very effective in withstanding hard usage. Lava buttons 8 encircle the filament legs at the points where they project through the wall of the glass envelop 7 in order to prevent any arc flowing from the filament 5 from coming into contact with glass projections 9. The electrode 6 is, in all respects, similar to the electrode 5. I have found the most satisfactory filaments for use in my device to consist of tungsten, but it is conceivable that, as will be hereinafter explained, the filaments 5 and 6 may comprise other materials which will operate satisfactorily.

A high-potential disturbance occurring upon the conductor 1 will pass freely through the discharge path 4 between the electrodes 5 and 6 to ground. Inasmuch as the filaments 5 and 6 are of comparatively small cross-sectional area, they will be rapidly heated as the discharge currents flow to ground 3. When the filaments have approached an incandescent heat, the arcs are suppressed or choked, and the line current is precluded from flowing to ground over the path initially established by the high-potential disturbances. I have found that, when the filaments 5 and 6 have reached incandescence, the arcs extending therebetween are completely disrupted and suppressed.

In Fig. 2, the electrode 6 of Fig. 1 is replaced by an electrode 10 which comprises a pool of mercury. A conductor 11, extending into the pool of mercury and sealed into the glass envelop 7, constitutes a means for connecting the electrode 10 to the ground 3. The action of this device I have found to be similar to that described in connection with the device of Fig. 1, the electrodes 5 and 10 serving, in this instance, to suppress the arc when the filament 5 has been heated to incandescence.

While I am not prepared to state, with certainty, the theory of operation of my device, the result appears to be due to the emission of an excess of negative ions from the

electrodes 5 and 6 when said electrodes are heated to incandescence. The first flow of currents through these electrodes is unimpeded, but, after the electrodes have become 5 heated to incandescence, the negative ions or electrons emitted therefrom appear to offer an extremely high impedance to the continuance of the current flow through the discharge path 4. When both electrodes 10 are of filamentary form, as shown in Fig. 1, they tend to become negative simultaneously. In the device shown in Fig. 2, the mercury pool 10 always acts as a cathode and, consequently, when the filament 5 is 15 transformed from an anode to a cathode by being heated to incandescence, both of the electrodes 5 and 10 are negative, as explained above.

Apparently, during the maintenance of 20 the high voltage, the forces acting upon the electrons within the device are sufficient to carry the said electrons from one electrode to the other, thus producing the double action of maintaining the respective electrodes at 25 electron-emitting temperatures by the electronic bombardment thereof and further producing current flow by said bombardment. As soon as normal voltage is restored, the forces acting upon the electrons 30 within the discharge device are insufficient to move the electrons from one electrode to the other against the repellent action of the large number of electrons in the neighborhood of the second electrode. Furthermore, 35 at the lower voltage, the electronic bombardment is much less powerful, thus failing to maintain the electron-emitting temperatures of the respective electrodes. The joint effect of these factors is to produce 40 an extremely rapid collapse of the vapor conductivity and the prompt suppression of line current flow after the cessation of the lightning discharge.

It will be understood that the electrodes 45 5, or those which are directly associated with the line conductor 1, should be made of such a form that they readily become heated when high-potential disturbances flow through them. I have found that electrodes 50 made in the form of filaments, such as are embodied in incandescent-lamp structures, are particularly adapted for use in my lightning arrester. It will be understood, however, that the cross-sectional areas 55 of the filaments 5 and 6 are dependent upon the service in which my lightning arrester is to be used.

Tungsten is a preferred material for the 60 filamentary electrodes embodied in my invention because it may be obtained readily in commercial quantities and is effective in service, since it may be continuously operated without deterioration, irrespective of the number and character of the disturbances 65 to which it may be subjected. I desire

it to be understood, however, that other materials which emit an excess of negative ions, when heated to incandescence, such as cerium oxid and thorium oxid, may be employed, though probably less suitable than tungsten for use in commercial apparatus.

If either cerium oxid, thorium oxid or other material of similar character is employed, it will preferably be applied as a surface coating to a metal conductor because such materials are not conductors of electricity under normal conditions. If such coated conductors are employed as filamentary electrodes of my lightning arrester, the operation will be substantially the same as has already been described.

While the envelop 7 may be evacuated, under certain conditions, it may be advisable to provide means for regulating the pressure therein in order to effectively extinguish the discharge arc. For this purpose, I may provide an extension 12 for the envelop 7 of Fig. 1, and in the extension, I may place a body of salt 13, such as zinc chlorate or calcium chlorate, or any other salt having a vapor pressure of substantially one millimeter of mercury through moderate ranges of temperature. In this manner, the pressure within the envelop 7 may be regulated.

While I have explained, somewhat in detail, the assumed theory of operation of my device, I do not desire to have my invention limited in any manner or degree because of such theory. Inasmuch as a device constructed in accordance with the above mentioned description is effective in suppressing arcs, it is not of material consequence whether or not the theory, as stated in my description, is, in all respects, correct.

It will be understood that many modifications may be made without departing from the spirit and scope of the appended claims.

I claim as my invention:

1. The method of operating a vacuum-type lightning arrester which comprises producing an excess of ions therein during the discharge of excess voltage, whereby the subsequent flow of line current is retarded.

2. The method of operating a lightning arrester having a discharge path in the form of a vapor conductor which comprises building up a space charge therein during the excess voltage discharge period, whereby the subsequent flow of line current is retarded.

3. The combination with an electrical system subject to normal voltage and to transient surges of abnormally high voltage, of means for discharging said surges without diverting energy at normal voltage comprising two electrodes, spaced apart sufficiently to prevent the formation of a discharge therebetween at normal voltage but to permit a discharge at abnormal voltage, said electrodes having sufficiently small heat ca-

pacity so that they are raised to an electron-emitting temperature during the discharge of abnormal voltage and by the subsequent free emission of electrons retard the passage of line current.

4. The combination with an electrical system subject to normal voltage and to transient surges of abnormally high voltage, of means for discharging said surges without diverting energy at normal voltage comprising two electrodes, spaced apart sufficiently to prevent the formation of a discharge therebetween at normal voltage but to permit a discharge at abnormal voltage, said electrodes having such heat capacity and radiation that the electronic bombardment at said abnormal voltage suffices to maintain them at an electron-emitting temperature but the electronic bombardment at line voltage fails to maintain them at an electron-emit-

ting temperature, whereby the line voltage is unable to maintain a discharge.

5. The combination with a circuit subject at times to relatively high voltage and at other times to relatively low voltage, of a discharge path connected thereto and comprising two spaced electrodes of such heat capacity and heat radiation that, during periods of high voltage, the initial electronic bombardment between said electrodes is sufficient to maintain them at electron-emitting temperatures but during periods of low voltage the initial electronic bombardment is insufficient to maintain said electrodes at electron-emitting temperatures. 35

In testimony whereof, I have hereunto subscribed my name this 27th day of April, 1915.

HAROLD A. NEWCOMB.
